UNITED STATES PATENT OFFICE.

HENRY CULLABINE, OF SHEFFIELD, COUNTY OF YORK, ENGLAND.

TOBACCO-PIPE.

SPECIFICATION forming part of Letters Patent No. 377,241, dated January 31, 1883.

Application filed April 11, 1887. Serial No. 234,475. (No model.) Patented in England August 19, 1886, No. 10,624.

To all whom it may concern:

Be it known that I, HENRY CULLABINE, of 5
Sheffield, in the county of York, England, have
invented new and useful Improvements in To-
bacco-Pipes, (for which I have obtained a pat-
ent in Great Britain, bearing date August 19,
1886, and numbered 10,624,) of which the fol-
lowing is a specification.

This invention relates to pipes having a re-
10 movable pin inserted in one end of the stem
for cleaning the latter.

The said invention consists in the peculiar
construction and combination of parts, herein-
after set forth and claimed.

15 In the accompanying drawings, Figure 1 is a
longitudinal section showing the bore through
the stem and the cap, with the needle or pin
placed in its position fitting on the outside of
the portion of the stem projecting beyond the
20 head or bowl of the pipe. Fig. 2 is a front
view of the pipe complete. Fig. 3 is the pin
A. Fig. 4 is an enlarged view showing the
cap B in elevation. Fig. 5 is an enlarged view
of the india-rubber C. Fig. 6 is a section of
25 Fig. 4.

In said drawings, E designates the pipe-
stem, which is straight, with an extension, E',
beyond the bowl D, the latter communicating
by a hole, d, in its bottom with the longitudi-
30 nal bore e of the said stem. This bore runs
through the entire length of said stem, includ-
ing the extension E'. The end of the exten-

sion E' is covered by a thimble-shaped cap, B,
which has a hollow annular expansion, b, just
beyond the said stem, and also a central per-
foration in its convex part in alignment with
said bore e. A long straight pin, A, is passed
through said hole and into said bore. When
in its normal position, the said pin leaves space
enough between it and the stem for smoke to 40
pass along the said bore. A disk, C, of india-
rubber, having a central hole, c, in alignment
with the bore and the hole in the cap, serves
to prevent the latter hole from interfering with
the draft through the bowl, inasmuch as said 45
rubber disk fits tightly on said pin, the latter
passing through said hole c. The peripheral
parts of said disk set in the hollow annular ex-
pansion b, and the said disk is held thereby.

Having now particularly described my in- 50
vention, what I claim is—

A cap, B, having a hollow annular enlarge-
ment, b, in combination with a disk, C, fitting
into said enlargement, and having a central
hole c, a pipe having an extension, E, on the 55
end of its stem and a bore, e, running from end
to end of said stem and extension, and a pin,
A, attached to said cap and passing through
the hole c of said disk into said bore, substan-
tially as set forth.

HENRY CULLABINE.
